Primary Examiner — Cathron C Brooks*Assistant Examiner* — Christian P. McLean(74) *Attorney, Agent, or Firm* — Venable LLP; Michele V. Frank(57) **CLAIM**

The ornamental design for a three-dimensional sign, as shown and described.

DESCRIPTION

FIG. 1 is a perspective view of the three-dimensional sign according to the claimed design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The features shown in broken lines represent portions of the three-dimensional sign which form no part of the claimed design.

1 Claim, 5 Drawing Sheets(56)
